UNITED STATES PATENT OFFICE.

DWIGHT B. McNAMEE, OF HEMAN, OKLAHOMA.

ENVELOP.

1,247,852.

Specification of Letters Patent. Patented Nov. 27, 1917.

Application filed February 17, 1917. Serial No. 149,295.

To all whom it may concern:

Be it known that I, DWIGHT B. McNAMEE, a citizen of the United States, residing at Heman, in the county of Woods and State of Oklahoma, have invented certain new and useful Improvements in Envelops, of which the following is a specification, reference being had to the accompanying drawings.

10 This invention relates to an improved envelop, and has for its primary object to provide an envelop particularly designed for the transportation of valuable papers or currency through the mails, whereby sewing of the latter to the paper envelop or container is obviated.

It is another object of my invention to provide an envelop for the above purpose constructed from a single blank sheet of paper folded upon itself in such manner as to completely inclose the contents, and provided with tie strings having one of their ends so fixed to one wall of the envelop as to be inaccessible, the tie strings being adapted to be tied together and sealed and coöperating with an exterior closure flap so as to prevent the latter being opened and subsequently resealed.

It is a further object of the invention to provide a device for the above purpose which is exceedingly simple in its construction, convenient and serviceable in practical use, and capable of manufacture at relatively small cost.

35 With the above and other objects in view, my invention consists in the novel features of construction, combination and arrangement of parts to be hereinafter more fully described, claimed and illustrated in the accompanying drawing, in which,

Figure 1 is a perspective view showing my improved envelop closed;

Fig. 2 is a longitudinal section;

Fig. 3 is a fragmentary interior elevation showing the manner of attaching the tie strings; and

Fig. 4 is a plan view of the blank from which the envelop is formed.

Referring in detail to the drawing, 5 designates the paper sheet which is of any desired texture so as to withstand rough handling, said sheet being cut in the form shown in Fig. 4 of the drawing to provide a front wall 6 at one end of which the sealing flap 7 is formed, said flap being gummed on one side along its edges, as

shown at 8. 10 and 11 respectively, indicate foldable, longitudinal sections of the paper sheet which together constitute the back or rear wall of the envelop. These 80 walls, together with the front or body wall 6, are creased as at 9, in spaced relation to the closure flap 7 and adapted to be folded over together with the flap, upon the section 11 of the back wall of the envelop. At the opposite end of the blank, the walls 6, 10 and 11 are also creased, as at 12, and the wall 11 is cut away, as at 13, so that the end portion thereof may fold upon the inner face of said wall 11. 70

The lower end portions below the crease 12 of the walls 6 and 10 are adapted to be folded upwardly upon the wall 10 and secured to said wall by means of a metal clip or fastener 14 having spurs or teeth indicated at 15 penetrating through the superposed paper layers and being clenched thereon. The wall 10 and the folded end portions of the paper sheet are provided with coinciding openings 16. The foldable flap of the wall 11 and the body of said wall are also provided with similar openings 17 to coincide with the openings 16 when the wall 11 is folded over upon the wall 10. A tie string 18 is securely fixed to the inner face of the wall 10 of the envelop by means of the metal clip 14 and extends through these coinciding openings in the several portions of the envelop blank. 80

The walls 10 and 11 are also securely fixed together adjacent the upper or open end of the envelop by means of a second metal clip 21 which secures a second tie string 20 to the inner face of the wall 10. These walls 10 and 11 and the foldable upper end of the body wall 6 are provided with openings 19 which are adapted to register when the flap 7 is folded upon the rear wall 11 and through which the tie string 20 is adapted to extend. The longitudinal edge of the wall 11 of the envelop at its upper end, is gummed so that when moistened it will adhere to the wall or flap 10. 90

The manner of using my improved envelop will be readily understood from reference to Fig. 1 of the drawing. The envelop, when manufactured for sale, may be folded and the walls thereof fastened together by means of the clips 14 and 21, or the parts of the envelop may be fastened together by the individual user. In any event, it will be understood that the papers, currency, or 105

other matter to be mailed is inserted into the open end of the envelop between the walls 6 and 10 thereof and the flap 7 then folded over upon the wall or section 11 along the 5 crease 9, the tie string 19 being inserted through the aperture in the closure flap. The gummed edge of this flap is, of course, moistened so that it will tightly adhere to the wall 11. The gummed edge of the wall 10. 11 is also moistened to adhere to the wall 10. The tie strings 18 and 20 are then brought together and tied and a suitable sealing wax applied thereto to confine the connected 15 strings upon the point of the closure flap 7 and the rear wall 11 of the envelop. With the envelop closed and sealed in this manner, it will be readily seen that it will be impossible for the envelop to be fraudulently 20 opened without detection. Any attempt to lift or raise the closure flap 7 would result in breaking the seal of the tie strings.

From the foregoing description, taken in connection with the accompanying drawing, the construction, manner of use and several 25 advantages of my improved safety envelop will be clearly and fully understood. The device being of very simple construction may obviously be manufactured at very small cost and affords a complete protection 30 to documents, currency, or other matter which is transported through the mails. By means of my device, the necessity of sewing the papers or currency to the walls of the envelop is entirely obviated and danger 35 of pilfering is reduced to a minimum. The envelop may, of course, be made in various sizes and is also susceptible of various modifications in its several features. I, therefore, reserve the privilege of resorting to all 40 such legitimate changes as may be fairly embodied within the spirit and scope of the invention as claimed.

Having thus fully described my invention, what I desire to claim and secure by Letters 45 Patent is:

1. A safety envelop consisting of a flexible sheet of material folded to provide a front wall and inner and outer rear walls, said

Copies of this patent may be obtained for five cents each, by addressing the "Commissioner of Patents, Washington, D. C."

walls having foldable end portions to close the envelop at one of its ends, a closure flap in the opposite end of the front wall, metal fasteners permanently securing the inner and outer rear walls to each other, sealing strings fixed by said fasteners upon the inner face of said inner rear wall, said walls having openings through which said strings extend, said closure flap also having an opening through which one of the strings is adapted to be disposed, said strings being adapted to be tied together and fixed to the rear wall of the envelop by a suitable sealing material to confine the closure flap in place.

2. A safety envelop consisting of a sheet of flexible material folded upon itself to provide a front wall and inner and outer rear walls, said walls being folded longitudinally of the envelop at one of their ends to permanently close said end of the envelop, a metallic fastener securing the folded ends to the inner rear wall, a tie string fixed to the inner face of said inner rear wall by the fastener, said inner wall and the folded end of the sheet having openings through which said tie string extends and said outer rear wall also having an opening therein through which the string is disposed, a second metal fastener securing the inner and outer rear walls together adjacent the opposite end of the envelop, the front wall at the latter end and the envelop being provided with a closure flap, said flap and the front and rear walls having openings therein, and a second sealing string secured to the inner face of the inner rear wall by the second named fastener to extend through said openings and adapted to be tied to the first named sealing string and said strings secured by a suitable sealing material to the rear wall and the closure flap of the envelop.

In testimony whereof I hereunto affix my 90 signature in the presence of two witnesses.

DWIGHT B. McNAMEE.
